United States Patent Office

Des. 218,369

Patented Aug. 11, 1970

218,369

FLIP CARD INDEX FILE

John Schwartz, 77 Park Terrace E.,
New York, N.Y. 10034

Filed Dec. 9, 1968, Ser. No. 15,010

Term of patent 14 years

Int. Cl. D19—99

U.S. Cl. D74—2

The figure on the drawing is a perspective view of a flip card index file embodying my new design, the sides opposite thereto being similar in appearance.

I claim:

The ornamental design for a flip card index file, as shown and described.
